UNITED STATES PATENT OFFICE

2,632,419

HIGH AND LOW LEVEL AUDIBLE BOILER
WATER ALARM

Eugene Topping, Brooklyn, N. Y.

Application October 25, 1951, Serial No. 253,090

4 Claims. (Cl. 116—70)

1

This invention relates to new and useful improvements in signalling devices and the primary object of the present invention is to provide a liquid level indicator for containers or hot water tanks whereby an alarm will be activated in response to a predetermined high or low liquid level in the tank, and more specifically the invention comprises a high and low level audible boiler water alarm.

Another important object of the present invention is to provide a boiler water alarm including upper and lower closed tubular members that are in communication with each other and a diaphragm signal actuator and which upper and lower members will be located above and below the normal level of a liquid in a container respectively, whereby the actuator will be actuated in response to increase or decrease pressure on the diaphragm in the event the level of liquid rises above both members or moves below both members.

A further object of the present invention is to provide a boiler water alarm that is quickly and readily attached to or removed from the boiler drum in a convenient manner to occupy very little space within a tank.

A still further aim of the present invention is to provide an indicator of the aforementioned character that is extremely simple and practical in construction, strong and reliable in use, efficient in operation, convenient to adjust for various actuating pressures, inexpensive to manufacture, install and service, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a fragmentary elevational view of a boiler drum and showing the present invention mounted thereon;

Figure 2 is a plan view of Figure 1;

Figure 3 is an enlarged vertical sectional view taken substantially on the plane of broken section line 3—3 of Figure 2;

Figure 4 is an enlarged vertical sectional view taken substantially on the plane of section line 4—4 of Figure 3; and,

Figure 5 is an enlarged vertical sectional view taken substantially on the plane of section line 5—5 of Figure 2.

Referring now to the drawings in detail, where-

2

in for the purpose of illustration, there is disclosed a preferred embodiment of the present invention, the numerals 10 and 12 represent upper and lower closed tubular members of metallic construction having heat conducting fins 14 and 16. Each of the members 10 and 12 is provided with a nipple in which the ends of a conduit 18 are suitably held to establish communication between the two members. The 10 upper member 10 is provided with a filling opening in which a plug 20 is removably positioned.

A housing 22 includes a removable upper wall 24 that is detachably connected to one end of a conduit 26 whose other end enters a nipple 28 on the member 12. A diaphragm 30 is mounted in the housing 22 and overlies the head 32 of a plunger 34 slidably carried by the housing. Hanger arms 36 depend from the housing 22 and support a cross-member 38 that is formed with 20 a central opening in which a guide sleeve 40 is threaded.

A coil spring 42 embraces the plunger 34 and is biased between the head 32 and an abutment 44 resting in the sleeve 40 to yieldingly urge the 25 head 32 against the diaphragm 30. The sleeve 40 is adjustable to vary the tension of spring 42.

The lower wall of housing 22 forms the upper wall of a valve housing 46 and supports an air whistle 48 or similar signal. A conduit 50 extending from a source of air under pressure 30 enters housing 46. Slidable valves 52 and 54 in the housing control the passage of air to the whistle and are spring urged into their seats. The lower ends of the valves extend outwardly 35 from the housing 46 above a rock lever 56 pivoted to the housing 46.

Lever 56 is formed with an eye end 58 that loosely receives the lower threaded end of plunger 34 on which upper and lower abutments 60 and 62 are threaded above and below eye end 58.

Means is provided for supporting the members 10 and 12 relative to a steaming tank T and for selectively heating and cooling the liquid in the closed system defined by members 10 and 12, tubes 18 and 26, and the diaphragm. This means comprises a substantially Z-shaped combined pressure and heat controller tube 64 having upper and lower horizontal portions 66 and 68 that extend axially through members or jacks 45 ets 10 and 12 and which have hollow lateral extensions 70 and 72 that communicate with the interior of the tank.

Flanges 74 and 76 are fixed to the extensions 70 and 72, and these flanges are suitably 50 cured to the steaming tank with member 10 and

portion 66 located above the normal liquid level of the steaming tank and with the member 12 and portion 68 located below the normal liquid level in the steaming tank.

In practical use of the present invention, a liquid is placed in the members 10 and 12, also tubes 18 and 26, and under normal temperature conditions and liquid level in the boiler T, the diaphragm 30 will be flexed slightly, as shown in Figure 5. The level of the liquid in the pressure and heat controller tube 64 will correspond to the level of liquid in the boiler T and the level of a water level indicating unit 78 mounted on the boiler.

When the boiler water level tends to rise in the boiler, the water level in the pressure and heat controller tube 64 will also rise and will enter the portion 66. This cold water plus the radiation of the fins 14, 16 causes the steam in portion 66 to condense, thereby reducing the pressure in the closed system allowing spring 42 to push diaphragm upward to blow whistle indicating high water level.

Should the boiler water level descend, the water level in pressure and heat controller tube 64 will likewise descend and the water in portion 66 will be replaced by steam that will enter the portion 66 from the boiler T. This will force water in the closed system 10, 18, 12, 26, 22 against the diaphragm causing an actuation of the whistle.

Having described the invention, what is claimed as new is:

1. In a device for indicating variations from a normal desired level of a liquid in a steaming tank, upper and lower closed tubular members, a conduit connecting the members, said tubular members and said conduit being filled with a liquid, means attached to one of the members adapted to be operatively connected to a pressure responsive signal actuator, and a pressure and heat controller tube supporting the members and having end portions extending through the members and adapted to communicate with the interior of a steaming tank.

2. In a steaming tank having a normal liquid level, an upper closed tubular member mounted

above the normal liquid level, a lower tubular member mounted below the normal liquid level, a conduit connecting the members, said members and said conduit being filled with a liquid,

5 and a pressure and heat controller tube having upper and lower portions extending through the members and communicating with the interior of the tank respectively above and below the normal liquid level, said lower member adapted 10 to be connected to a pressure responsive signal actuator to actuate the same when the liquid level goes above the upper member or below the lower member.

3. The combination of claim 2 and attaching 15 flanges at the ends of said tube mounted on the tank.

4. A boiler water alarm comprising upper and lower closed tubular metallic members one of which is adapted to be supported horizontally above the normal level of a liquid in a boiler 20 and the other of which is adapted to be supported below the normal level of a liquid in a boiler, a conduit connecting the members, said conduit and said tubular members being filled with a liquid, a pressure and heat controller tube 25 supporting the members and having end portions extending longitudinally through the members and adapted to communicate with the interior of a boiler, a housing communicating with the lower member, a diaphragm in the housing, and a signal actuator slidably carried by the housing and engaged by the diaphragm, said diaphragm adapted to be flexed to actuate the actuator in response to pressure change in the 30 housing from the liquid in the members.
